DESIGN FOR A BOOK SUPPORT

Philip La Delfa, Dansville, N. Y.

Application November 11, 1932. Serial No. 45,885

Term of patent 3½ years

To all whom it may concern:

Be it known that I, PHILIP LA DELFA, a citizen of the United States, residing at Dansville, in the county of Livingston and State of New York, have invented a new, original, and ornamental Design for a Book Support, of which the following is a specification.

Reference is had to the accompanying drawing, forming a part of this specification.

In the drawing:

I claim:

The ornamental design for a book support, as shown.

In testimony whereof I affix my signature.

PHILIP LA DELFA.
